UNITED STATES PATENT OFFICE.

SVEN JULIUS STRID, OF CHICAGO, ILLINOIS, ASSIGNOR TO FRED MATHEWS, OF CHICAGO, ILLINOIS.

MOUNTING FOR BRAKE GEARS.

Application filed March 22, 1926. Serial No. 96,512.

My present invention relates to brake gears for railway cars, and it has more particular reference to the mode of installing the gears upon the end portion of the car. 5 As is well known, there are numerous types of car and underframe constructions, and each railway company has special designs of structures to suit the requirements of the particular traffic handled by it in the 10 most efficient and dependable manner. Thus, when it is desired to install a brake-gear upon the end of a car of any particular or special design it is necessary to devise means that will effectively carry the gearing and will brace the same against the 15 longitudinal stress of the pull rods and chains of the brake mechanism.

My present structure is especially designed for use in connection with a certain type 20 of gondola car, and has for its object the provision of means for mounting the brake gear, which means are compact in arrangement, dependable in operation, economical to manufacture, and which is novel in construction. I prefer to carry out my invention 25 and to accomplish the several objects thereof in substantially the manner herein-after fully described and as more particularly pointed out in the claims, reference 30 being here made to the accompanying drawings that form a part of this specification.

In the drawings:—

Figure 1 is a longitudinal side elevation of 35 a portion of a car underframe showing my invention thereon with the center-sill in elevation and the end-sill in transverse section.

Figure 2 is a top plan of the structure illustrated in Figure 1.

Figure 3 is a vertical transverse section 40 taken on line 3—3 of Figure 1 looking in the direction of the arrows.

The drawings are somewhat schematic for the purpose of illustrating a typical or preferred embodiment of my invention, and in 45 said drawings like reference characters have been employed to designate similar parts wherever they appear throughout the several views.

The portion of the car underframe herein 50 illustrated comprises a longitudinally disposed center-sill member in the form of a metal channel beam positioned with its web 5 in a vertical plane and its upper and lower flanges 6 and 7 laterally disposed in horizontal planes. The center-sill member 5

may be one of the elements of a composite sill, or it may be of the I-beam type, and is cut away at its end so as to provide a horizontal shelf 8 to carry the transversely disposed end-sill member 9 that is connected 60 to the web 5 by means of the angular strap 10. In the underframe structure illustrated there is an intermediate transverse angular member 11 that extends from the center-sill member to the adjacent side-sill or side of 65 the car, and as seen in Figure 3, and as viewed from the end of the car, this intermediate member or sill 11 is given an edge bend as at 12 so that it extends upwardly from the bend towards the side-sill or side 70 of the car, and also upwardly from the bend towards the center-sill where it is secured to the web of the latter. A bracket formed from an angle-shaped plate has one flange 13 secured to the web 5 of the center-sill member and its other flange 14 projects laterally therefrom and has the adjacent oblique end 75 portion of the intermediate member 11 secured to it.

The gearing for operating the brake is 80 mounted within a housing consisting of top and bottom castings, the former comprising a horizontal disposed rectangular plate 15 with depending side portions 16 that are secured to corresponding upstanding side portions 17 of the lower plate 18. The gearing itself forms no portion of the present invention and needs no reference herein except to state that the same is of the type set forth in United States Patent No. 1,508,624, 85 which was issued September 16th, 1924 to Fred Mathews for a "Gearing." The plate 15 of the upper casting is preferably positioned with one of its longitudinal edges parallel with and spaced below the lower 90 flange 7 of the center-sill and the transverse edge of the plate 15 is spaced inwardly from the vertical plane of the end-sill 9. The plate 15, as seen in the drawings, is in the horizontal plane of the lower edge of 95 the intermediate member or sill 11 at the bend in the latter which is below the horizontal plane of the lower flange 7 of the center-sill. The bend 12 affords a means 100 for connecting the intermediate member 11 with the gear housing which is done by providing a lateral lug 19 upon the longitudinal edge of plate 15 farthest from the center-sill, which lug has its upper surface 105 slightly concaved and extends obliquely in an 110

upward direction as shown in Figure 3 to provide a seat for and conforms to the shape of the bent flange that is secured to this lug by the rivet 20. The edge of plate 15 nearest the end-sill is provided, upon its corner farthest in the center-sill, with a lug 21, and a brace 22 is secured at its lower end to said lug and extends obliquely in an upward direction towards the web of the center-sill where it is given an edge bend to provide a vertical extension 23 that is disposed parallel with the center-sill web to which latter is riveted, bolted, or otherwise secured. The longitudinal edge of plate 15 adjacent the center-sill is provided with front and rear feet 24 and 25 respectively the upper flat surfaces of which are disposed in a plane above the plane of plate 15 a distance sufficient to engage with the lower surface of the lower flange 7 of the center-sill to which flange these feet are secured by bolts, rivets or otherwise. From the foregoing it will be obvious the gear housing is connected in a rigid manner to the car-underframe by means of a mounting structure that is dependable in preventing the housing from tilting or being accidentally moved out of its desired position incident to the stress exerted by the pull on the chain and other parts of the brake mechanism. In order to further reinforce and brace the gear-housing I provide an angle-bar 26 similar to the brace 22 that is secured at its lower end to the outer portion of the plate 15 and extends obliquely in an upward direction to the web of the center-sill, where it is given an edge bend to provide an upward extension 27 that is secured to the web of the center-sill in the same manner as the extension 23 of the front brace. The housing is thus reinforced at all four corners by its attachment to the center-sill and to the braces 22 and 26 and there is an intermediate reinforcement provided through the medium of the intermediate member or sill 11.

What I claim as new is:—

1. Means for mounting a brake-gear comprising a car center-sill, a transverse beam extended laterally therefrom, a gear housing the upper portion is secured to said center-sill and said beam, and an oblique brace extended from said housing to said center-sill, said brace disposed in a vertical plane parallel with said beam and transverse to said center-sill.

2. Means for mounting a brake-gear comprising a car center-sill, a transverse beam extended laterally therefrom, a gear housing the upper portion of which is secured to said center-sill and said beam, and a pair of oblique braces extended from opposite ends of said housing upon opposite sides of said beam to said center-sill.

3. Means for mounting a brake-gear com-

prising an angle-metal center-sill disposed with its web in a vertical plane, a gear housing secured to one of the longitudinal edges of said center-sill and extended horizontally therefrom, and a transverse beam extended laterally from said center-sill and bent intermediate its ends towards and secured to said housing. 79

4. Means for mounting a brake-gear comprising an angle metal center-sill disposed with its web in a vertical plane, a gear housing secured to one of the longitudinal edges of said center-sill and extended horizontally therefrom, a transverse beam extending laterally from said center-sill and bent intermediate its ends towards and secured to said housing, and an oblique brace extended from said center-sill and secured to said housing, said brace disposed in a vertical plane parallel with said beam. 85

5. Means for mounting a brake-gear comprising an angle-metal center-sill disposed with its web in a vertical plane, a gear housing secured to the lower flange of said center-sill, and a transverse beam secured to said sill above said housing and extended downwardly to and secured to said housing and extended therefrom in a direction lateral to said center-sill. 90

6. Means for mounting a brake-gear comprising a center-sill having a vertically disposed web portion and a lateral lower flange, a gear housing secured to said flange, braces connected to outer portions of said housing and to the upper portion of the center-sill 100 web, and an under frame beam connected to said center-sill web and extended towards the side of the car in a plane intermediate said braces, said beam being bent transversely downwardly to and secured to said 105 housing. 100

7. Means for mounting a brake-gear comprising a car center-sill, an intermediate underframe beam secured to said sill and projecting transversely thereto towards the 110 side of the car and having a portion extended downwardly below said sill, a gear-housing secured to the lower portion of said beam and disposed in a horizontal plane below said sill, and means upon said housing 115 extending to said sill and connecting said housing thereto.

8. Means for mounting a brake-gear comprising a car center-sill, an intermediate underframe beam secured to said sill and projecting therefrom towards the side of the 120 car and having a portion extended downwardly below said sill, a gear-housing secured to the lower portion of said beam and disposed in a horizontal plane below 125 said sill, means upon said housing extended to said sill and connecting said housing thereto, and braces secured to and extending obliquely from an edge portion of said housing towards and secured to said center-sill. 130

9. Means for mounting a brake-gear comprising a car center-sill, a gear housing secured along one longitudinal edge to said sill, and bracing means extended from other longitudinal edge of said housing and inclined obliquely towards and secured to said sill.
10. Means for mounting a brake-gear comprising a car center-sill, a gear housing secured along one longitudinal edge to said sill, and braces extending from opposite ends of the other longitudinal edge of said housing and inclined towards and secured to said center-sill.
11. Means for mounting a brake-gear comprising a car center-sill, a gear housing secured along one longitudinal edge to the

lower edge of said center-sill, and bracing means secured to and extended from the other longitudinal edge of said housing and inclined towards the upper edge of said center-sill and secured thereto. 20

12. Means for mounting a brake-gear comprising a car center-sill, a gear housing secured along one longitudinal edge to the lower edge of said center-sill, and brace secured to and extending from opposite ends of the other longitudinal edge of said housing and inclined towards the upper edge of said center-sill and secured thereto. 25 30

Signed as Chicago, in the county of Cook, and State of Illinois, this 19th day of March 1926.

SVEN JULIUS STRID.
